UNITED STATES PATENT OFFICE.

THOMAS E. BLANCHARD, OF RIFLE, COLORADO.

DESIGN FOR A WASHER.

SPECIFICATION forming part of Design No. 33,951, dated January 22, 1901.

Application filed December 15, 1900. Serial No. 40,052. Term of patent 14 years.

To all whom it may concern:

Be it known that I, THOMAS E. BLANCHARD, a citizen of the United States, residing at Rifle, in the county of Garfield and State of Colorado, have invented and produced a new and original Design for a Washer; and I do hereby declare the following to be a full, clear, and exact description of the same, reference being had to the accompanying drawing, forming a part thereof.

This invention relates to a new and original design for a washer made of metal for use at a joint or in connection with a bolt, pivot, or similar article, and the accompanying drawing is a perspective view thereof.

As shown in the drawing, the design comprises a flat substantially circular plate A, having a central perforation B, and at the

outer edge of each face of the plate teeth C, projecting above the faces and substantially perpendicular to the plane thereof.

The essential features of the design are the perforated plate and the projecting teeth around the outer edge thereof.

Having thus described the invention, what is claimed as new, and which I desire to secure by Letters Patent, is—

The design for a washer, as herein shown and described.

In testimony whereof I affix my signature in presence of two witnesses.

THOMAS E. BLANCHARD.
